UNITED STATES PATENT OFFICE.

JOHN H. BARR, OF NEW YORK, N. Y., ASSIGNOR TO REMINGTON TYPEWRITER COMPANY, OF ILLION, NEW YORK, A CORPORATION OF NEW YORK.

TYPEWRITING MACHINE.

1,407,509.

Specification of Letters Patent. Patented Feb. 21, 1922.

Application filed July 6, 1918. Serial No. 243,587.

To all whom it may concern:

Be it known that I, JOHN H. BARR, citizen of the United States, and resident of the borough of Manhattan, city of New York, in the county of New York and State of New York, have invented certain new and useful Improvements in Typewriting Machines, of which the following is a specification.

10 My invention relates to typewriting machines and it has for its principal object to provide an improved typewriting machine capable of being expanded into position or condition for use and to be compacted into 15 a smaller space for convenience in carrying about.

To the above and other ends my invention consists in certain features of construction and combinations and arrangements of 20 parts all of which will be fully set forth herein and particularly pointed out in the claims.

25 A typewriting machine having my invention embodied therein is illustrated in the accompanying drawings, but with some parts of the complete machine not shown.

In said drawings,

Figure 1 is a side elevation of the machine with the casing removed, the machine 30 being shown in expanded position.

Figure 2 is a partial plan view of the same.

Figure 3 is a view like Fig. 1 but with the machine in compacted position.

35 Figures 4 and 5 are front to rear vertical sectional views, the former showing the machine compacted, and the latter expanded.

40 Figure 6 is a perspective view of a portion of the mechanism whereby the expanding and collapsing of the machine is effected, the parts being shown in expanded position.

Figure 7 is a reduced diagrammatic side view of the machine in extended position, 45 the linkages concerned in the compacting of the machine being represented by heavy lines.

Figure 8 is a similar view, showing the machine compacted.

50 My invention is here shown embodied in a machine which in many respects is similar to that shown in my prior application filed May 21, 1918, Sr. No. 235,812; but some of the features of the present invention are 55 capable of embodiment in machines differ-

ing considerably both from that shown in said prior application and also from the one shown in the present drawings.

The framework of the machine shown in the drawings may be said to comprise three 60 principal parts, all of which are stationary when the machine is in use but which are relatively movable from compacted position to expanded position, and vice versa, said three parts consisting of a base 1, a type 65 action frame 2 and a type bar rest 3. The base 1 consists of a sort of sheet metal pan with upturned flanges and provided with rubber feet 4 by which it rests on the desk. The bottom of this pan may or may not be 70 cut away for the sake of lightness.

The type action frame 2 comprises right and left-hand side plates 5, a transverse front bar 6 and a casting 7, Fig. 2, which latter connects the side plates 5 near their 75 rear ends. This casting is so shaped and machined as to comprise a type bar segment 8 and a sub-lever segment 10 lying substantially in horizontal planes, the latter in front of the former. This casting also 80 includes right and left-hand extensions 11 which are secured to the side plates 5. It will be seen that the type action frame 2 may be roughly described as a rectangular frame, as viewed from above. 85

Referring to Figs. 1 and 3 and also to Figs. 7 and 8, the base 1 and frame 2 are connected by forward links 12 and rear links 13, the four links being parallel and being pivoted to the base 1 at 14 and to the frame 90 2 on pivot screws 15. When the machine is expanded these links stand nearly upright or a little past the center, and when the machine is compacted they lie toward the front of the machine and more nearly horizontal, 95 the frame 2 in this position being down against and almost in the pan-like base 1. When the machine is moved to its expanded position the motion of the parts is arrested by lugs 16 of the links 12 striking against 100 projecting parts of the front plate 6 of the frame 2. Any suitable means can, if desired, be provided for fastening the frame 2 in its elevated position but no such means is shown in the present drawings. 105

A platen 17 is mounted in a carriage 18 which is connected by ball bearings 20 with carriage rails 21 secured to brackets 22. Said brackets constitute parts of a shift frame the balance of which is not shown 110

herein but which is shown and described in my aforesaid application Serial No. 235,812. Said shift frame is mounted in the type action frame 2 and is capable of being shifted 5 front and back under the control of a case shift key 23, Fig. 2.

The type bars 24 each carry two types and they are pivoted on a pivot wire 25 lying in a groove in the rear face of the type bar 10 segment 8, which segment has a series of radial slots 26, Fig. 5, to guide said type bars. Each of the type bars has on the heel thereof several gear teeth 27 followed by a concentric part 28. The sub-lever segment 15 10 has a series of sub-levers 30 mounted therein in radial slots 31 and pivoted on a wire 32, and each provided with a restoring spring 29. Each of said sub-levers at its rear end is made of segmental form having 20 a concave edge 33 adapted to the smooth part 28 of the type bar and having also gear teeth 34 adapted to the gear teeth 27. It will be recognized that the gearing between 25 the sub-levers 30 and the type bars 24 is of the general sort sometimes called Geneva gearing.

Each of the sub-levers 30 is connected by a depending link 35 with a secondary sub-lever 36 which in turn is connected by a 30 vertical link 37 with a printing key lever 38, said key levers having keys 40 on their forward ends. The front plate 6 of the frame 2 has the form of a double comb plate having long slots in its lower part, 35 which guide the key levers 38, and having shorter slots in its upper part, in which the sub-levers 36 are pivoted. Said sub-levers 36 extend directly front and back of the machine whereas the sub-levers 30 radi- 40 ate from the printing center of the machine as will be understood from Fig. 2. It will also be understood that the sub-levers 30 are all alike, whereas the sub-levers 36 are of varying lengths, those near the middle 45 of the system being the shortest and said sub-levers increasing in length towards the sides of the system. The links 35 are all at the rear ends of the several levers 36 and the links 37 are variously located in order 50 to bring about the desired equality of leverage of the several keys on their respective type bars.

The key levers 38 extend toward the rear of the machine beneath the casting 7 and 55 they are all pivoted at their rear ends on a wire 41 secured in a comb plate 42 having the form of an angle iron, the horizontal flange of which is secured by screws 43 to the under side of the casting 7.

60 From what has been said it will be perceived that when the frame of the machine is changed from compacted to expanded condition and vice versa the entire type action and also the platen and carriage move with 65 the frame 2.

The type bar system is itself expandable and compactible by moving the type bars individually to change the formation of the system or set of type bars from the expanded formation illustrated in Figs. 1, 2 and 5 to 70 the compacted formation illustrated in Figs. 3 and 4. The Geneva gearing between the type bars and their sub-levers 30 constitutes part of the means whereby this change of formation of the type bar system is made 75 possible. In the expanded formation each type bar stands up as shown in Fig. 5 where it will be seen that the first of the teeth 27 is in engagement with the rack on the end of the sub-lever. But if the type bar be 80 dropped down from its Fig. 5 to its Fig. 4 position the sub-lever will be moved but a slight distance when the smooth part 28 of the heel of the type bar runs into mesh with the concave 33 of the sub-lever, where- 85 upon the type bar moves independently of the sub-lever and is capable of dropping down to the horizontal position shown in Fig. 4 without causing further downward motion of the rear end of the sub-lever 30 and upward motion of the key 40. In this position, the type bar locks the sub-lever 30 and, therefore, the printing key 40, against 90 operation.

The change in formation of the set of 95 type bars is effected by moving the type rest 3 up and down and means are provided for so moving the said type rest in conjunction with the up and down movement of the frame 2, so that the compacting of the frame 2 with relation to the base 1 and the compacting of the type bar system itself with relation to the frame 2, automatically take place together. Said type rest 3 is here shown as consisting of an arc-shaped bar 105 or rod covered with suitable soft or elastic material and supported at its ends in arms or brackets 44 to which said type rest is secured by screws 45, Figs. 1 and 2, each passing through one of the brackets 44 and threaded into the end of the rod. The brackets 44 consist of prolongations of links 46 one on each side of the machine and each pivoted or jointed at 47 to an upward and forward extension 48 of the link 13 which 115 connects the base 1 with the frame 2. It will be perceived that the pivot 47 is further from the pivot 14 than is the pivot 15 so that the link 46 will move up and down further than the frame 2. Moreover, the extension 48 of the link 13 extends much more nearly horizontal than the part of said link between the pivots 14 and 15. By comparing Figs. 1 and 3 it will be perceived that the actual motion of the type rest 3 from the position shown in Fig. 1 to that of Fig. 3 is in a direction downward and toward the front of the machine, but that its motion with relation to the frame 2 is nearly vertical. By comparing Figs. 4 and 5 it will be

seen that in the compacted position of the machine the type rest is nearly in the same horizontal plane as the pivot wire 25 of the type bars whereas in the expanded position 5 said type rest stands considerably above said pivot wire.

The upper part of the link 46 and bracket 44 is guided in the compacting and expanding movements by links or arms 50, one at 10 each side of the machine and pivoted at 51 to the links 46. Said links 50 extend toward the front of the machine where they are secured rigidly to the ends of a transverse rock shaft 52 journaled at its ends in the side 15 plates 5 of the frame 2. As here shown the links 50 are secured in place on the ends of said shaft by screws 53. The end of the shaft may be squared or otherwise shaped so that the links 50 are rigid on said shaft 20 whereby the two ends of the type rest are compelled to move up and down to the same extent.

In my prior application, Serial No. 235,812, hereinbefore referred to, the type 25 rest had an up and down motion for the same purpose as the type rest 3 in the present case; but in said prior application the type rest was mounted on a top plate which moved bodily up and down, and the links 30 50 were not employed.

From all that has been said it will be seen that when the machine is in its expanded position, shown in Fig. 1, the type 35 action is at a convenient elevation above the desk and the type bars stand up at a convenient angle to be operated by the keys, which cause them to be thrown toward the rear and downward to strike against the upper face of the platen 17; whereas when the 40 machine is in its compacted position the entire type action frame 2 is lowered as much as possible and also the type bars themselves are dropped back into horizontal positions, so that the up and down dimension 45 of the machine, as a whole, is greatly reduced. It will also be perceived that in the compacting movement the platen and carriage move not only downward but toward the front of the machine, coming nicely 50 into the pan-like base 1 as shown in Fig. 3.

I have provided for still further compacting the machine in a front and back direction by changing the formation of the keyboard, by contracting or fore-shortening 55 said keyboard. To this end the forward keys 40 and also the space bar 54 are brought in under the rear keys 40, whereby the length of the machine is materially reduced. Moreover, as will hereinafter appear, this 60 compacting of the keyboard takes place automatically in conjunction with the other compacting movements of the machine.

Some of the key levers 38 are so constructed as to be capable of a telescopic longitudinal contraction and expansion, as best

shown in Fig. 6. In the present instance this construction is confined to the forward two rows of the four rows of keys 40. Each of the levers of the two forward rows is made in two parts, the rear part pivoted on 70 the wire 41 and extending to just in front of the cross bar or comb plate 6 where it terminates in a loop 55 extending upward and embracing the forward part of the key lever, which forward part projects toward 75 the front of the machine and has the key 40 mounted thereon. This forward part of the key lever lies on top of and edge to edge to the lower and rear part of said key lever, extending into the machine some distance behind the comb plate 6 and having on its rear end a loop 56 extending downward and embracing the rear section of the key lever. The construction is such that the key can be pushed toward the rear of 80 the machine as will be understood by comparing Figs. 4 and 5, the upper and forward section of the key lever sliding over the upper edge of the lower and rear section, said upper section sliding through the 85 forward loop 55 and the rear loop 56 sliding over the rear section of the key lever.

The space bar 54 is here shown as consisting of an angled piece of sheet-metal secured at its ends to two levers or side bars 95 57 which are pivoted at their rear ends on the wire 41 and which are of the telescopic construction just above described, each of said levers 57 being made in two sections, the same as the telescopic key levers 38. This 100 construction of space bar and key lever whereby the keyboard is made contractible is more fully shown and described and is claimed in my prior Patent No. 1,267,356, dated May 28, 1918. In the present case this 105 construction is claimed only in combination with other expandible and contractible features of the machine. In the present instance, however, there are detail differences between the construction of the space bar 110 of the present machine and that shown in my prior patent just referred to, and these differences will be understood by reference to Fig. 6. The rear sections 58 of the space key levers 57 have each a part 60 bent off from 115 part of its under edge toward the outside of the machine, said part being thence bent upward as shown to form a flange. This bent-over part of the lever, extending as it does a little down from the lower edge of 120 the section 58, has notches cut therein to form a series of rack teeth 61. Moreover, the upper section 57 of each of said levers has a similar flanged rack on its upper edge which is bent first outward toward the side 125 of the machine and thence downward and so cut as to form rack teeth 62. A pinion 63 has its teeth engaging the rack teeth 61 and 62, said pinion being guided and held in place in engagement with the upper and 130

lower racks by the vertical flanges of the racks. It will be perceived that the construction is such that each of the racks comprises a sort of groove between the 5 bent-over flange and the main body of the lever and this groove is of such character as to prevent the displacement sidewise of the pinion 63. Said pinion is journaled on a stud secured in place by a screw 64, 10 which screw passes through the forward end of an approximately horizontal link 65 and which at its rear end is pivoted at 66 to a lever 67 which at 68 is pivoted to the side plate 5 of the frame 2. When the machine 15 is in the expanded position shown in Figs. 1 and 6 the pinion 63 is in engagement with the forward end of the rack 61 and with the rear end of the rack 62; but if the space bar 54 be pushed toward the rear of the 20 machine to the position shown in Fig. 3 the rack 62 will cause the pinion 63 to roll along the rack 61, the pinion moving toward the rear of the machine just half as far as the space bar moves. In this rear- 25 ward motion the pinion carries with it the link 65 and the lower end of the lever 67. Said lever 67 is integral with a segmental rack 70 lying forward of the pivot 68 and meshing with another rack 71 secured, as by 30 rivets 72, to the link 50 which guides the up and down movement of the link 46 and type rest 3. It will be perceived therefore that if, with the parts standing as shown in 35 Figs. 1 and 7, the space bar 54 be pushed toward the rear, the lever 67 will be rocked, the racks 70 and 71 and the link 50 will be moved downward and the type rest 3 will move downward also. Moreover, the links 50 being connected to the links 46, and these 40 being connected as described with the links 13, said links 13 will also be carried down at the same time moving the entire upper parts of the machine to the compacted position shown in Figs. 3 and 8. If, on the other 45 hand, the frame 2 itself be moved up or down carrying the links 46 with it as has been described, it will be obvious that this motion will be communicated through the racks 71 and 70, lever 67, etc., to the space 50 bar, causing the said space bar and telescoping printing key levers to be moved forward or rearward. It will, of course, be understood that the lever 67 or its equivalent can be connected to the space key levers by 55 means other than the pinions 63, etc., here shown; but said pinions are advantageous in reducing the long motion of the space frame to a shorter motion of the lever 67.

In the present machine as in that shown 60 in my prior patent hereinbefore referred to, the space bar 54 in its telescopic movement carries the telescopic key levers 38 with it. To this end each of said key levers of the front two rows has a vertical edge 73 which 65 is acted on by the rear edge of the space

bar to push said key levers into the machine to the position shown in Fig. 4. In order to pull said printing key levers out to their expanded positions when the space bar moves forward, a bar 74 is provided which 70 lies across the tops of all of the rear sections of the printing key levers 38 and just at the rear of the rear ends of the forward or telescoping sections of such of said key levers as have the telescopic action. Said 75 bar 74 is secured to the rear ends of two links 75 one at each side of the machine and each pivoted at 76 to one of the telescopic sections 57 of the space key levers. When the space bar is moved toward the front of 80 the machine it draws this bar 74 with it and said bar, acting on the rear ends of the upper sections of the printing key levers, pulls all of said key levers out into their positions for use as shown in Figs. 1 and 2.

It will be perceived that when one machine is in its expanded condition ready for use, as shown in Figs. 1 and 5, the frame 2, which carries most of the mechanism, is at a suitable elevation above the desk and above 90 the base 1, the type bars are held up in position to be operated without having to move through a very large angle and the keyboard is expanded in the usual formation of typewriter keyboards; and it will also be 95 perceived that when the machine is moved to compacted position the frame 2 drops down into and onto the base 1; the space bar and the forward rows of keys are moved into contracted relationship with the other 100 keys and with one another; and the type bars are dropped down into their compacted formation and into close relation with the rest of the machine so that the entire space occupied by the machine is greatly reduced. 105

It will be seen that the links 65 and 75 are both so connected with the space key levers and that they are so disposed as to allow of the down and up motion of said space key levers without disturbing either the levers 67 110 or the bar 74. In respect to said bar 74 the present machine is an improvement over that shown in my prior Patent No. 1,267,356, hereinbefore referred to. In said patent a bar which performs the general function of the bar 74, is mounted on the forward sections of the space key levers themselves so that this bar moves up and down with the space key and in case it was in actual contact with the rear end of the telescopic section of one of the printing key levers it would rub against said section. In the present instance the bar 74 simply rests on top of the rear sections of the printing key levers and does not move up and down with the 115 space bar, this being due, of course, to the fact that the links 75 are pivoted to the space key levers as described.

There are a number of parts of the machine shown in the drawings and which have 120

not heretofore been referred to. A letter feed rack 77 is mounted on the carriage 18 and it has its rack teeth on the upper edge thereof in position to be engaged by any 5 suitable feed dogs 78, conventionally shown in the drawings. Said feed dogs, and in fact the entire carriage feed mechanism, can be of any suitable description but as here shown said dogs are loosely mounted on a 10 transverse rock shaft 80 which at its ends is connected, by means not shown, with lever arms 81 on the forward end of which is mounted a universal bar 82, that underlies the printing key levers and the space key 15 levers. Said rock shaft 80 has rigidly mounted thereon an arm 83 loosely connected at 84 with an arm 85 of the device on which the feed dogs 78 are mounted, the loose connection 84 being of such character 20 that said feed dogs do not partake of the entire oscillation of the shaft 80. All of this mechanism is more fully shown and described in my prior application Sr. No. 235,812, hereinbefore referred to.

25 The drawings also show a center guide 86 for the type bars, ribbon spools 87 and a driving shaft 88 operated by any suitable means and geared in any suitable way to the spools 87. The machine can be equipped 30 with any suitable paper feed devices 90. In Fig. 2 there is shown a fragment of a top plate 91 which is secured to the side plates 5 of the frame 2 through the instrumentality of ears 92 bent off from said side plates.

35 Various changes can be made in the details of construction and arrangement without departing from my invention.

What I claim as new and desire to secure by Letters Patent, is:—

40 1. In a compactible typewriting machine, the combination of a set of type bars, a set of keys for operating said type bars, means for changing the formation of said set of type bars to an extended formation ready 45 for use and to a compacted formation, and connected means for changing the formation of said set of keys.

50 2. In a compactible typewriting machine, the combination of a set of type bars, a set 55 of key levers including telescopic key levers connected with said type bars, and mechanism for simultaneously telescoping said telescopic key levers and changing the formation of said set of type bars from an extended formation ready for use to a compacted formation.

55 3. In a compactible typewriting machine, the combination of a set of printing key levers and connected printing instrumentalities, means for compacting the dimensions 60 of said set of key levers towards the back of the machine, and means operatively connected with the first recited compacting means for compacting the machine vertically.

65 4. In a compactible typewriting machine

including a keyboard and printing instrumentalities, the combination of means for shortening the dimensions of said keyboard to compact the machine horizontally, and means operatively connected with said shortening means for compacting the machine vertically. 70

5. In a compactible typewriting machine, the combination of a keyboard, type mechanism, and compacting means including 75 means for depressing the type mechanism into compacted position and for fore-shortening the keyboard.

6. In a typewriting machine, the combination of a pivoted type bar, a telescopic 80 key lever for operating said type bar, and means for simultaneously dropping said type bar back to a compacted position and for telescopically fore-shortening said key lever. 85

7. In a compactible typewriting machine, the combination of a telescopic key lever, a pivoted type bar connected with said key lever, and means for simultaneously dropping said type bar back to a compacted position, disconnecting said type bar from said key lever and telescopically fore-shortening said key lever. 90

8. In a compactible typewriting machine, the combination of a keyboard, type mechanism connected with said keyboard, means for moving said type mechanism into a compact position, means for fore-shortening said keyboard, and geared connections between the last two recited means. 95

9. In a typewriting machine, the combination of a set of pivoted type bars, a type rest movable to bring said set of type bars into extended formation and into compact formation, a space bar that can be moved toward the rear of the machine into compact position, and a geared connection between said space bar and said type rest. 105

10. In a compactible typewriting machine, the combination with a set of type bars, printing keys for operating said type bars, and a space bar, of means for compacting said set of type bars and connected means for bringing said space bar into compact relation to said printing keys. 110

11. In a compactible typewriting machine, the combination with a frame, of a compactible set of type bars, a compactible set of keys for operating said type bars, and means for simultaneously compacting 120 said keys and type bars.

12. In a compactible typewriting machine, the combination of a contractible keyboard, a compactible type mechanism, and a compactible frame. 125

13. In a compactible typewriting machine, the combination of telescopic key levers, compactible type mechanism, and a compactible frame.

14. In a typewriting machine, the com- 130

- bination with a frame including two parts, one of which can be moved into and out of compacted relation with the other, keys mounted in one of the parts of said frame, 5 and means for compacting said set of keys with respect to said frame-part.
15. In a compactible typewriting machine, the combination of telescopic key levers, a bar extending across said levers and 10 movable to telescope them, a compactible frame, and means whereby the motion of said bar to telescope said key levers is connected with the means for compacting said frame.
15. 16. In a compactible typewriting machine, the combination of a frame including two parts, movable connections between said two parts permitting motion into a compacted relation of said two parts, keys 20 mounted in said frame, and means operatively connected with said movable connections for moving said keys into a compacted formation, whereby a compacting or expanding of the keys causes a compacting or expanding of the frame or vice versa.
17. In a compactible typewriting machine, the combination of a frame including two parts, parallel links connecting said 30 two parts and permitting one of them to move into and out of compacted relation to the other, a set of keys mounted in said frame, and means connected with said links for compacting said set of keys.
35. 18. In a compactible typewriting machine, the combination of a frame including two parts, means connecting said two parts to allow of a motion of one of said parts into downward compacted relation to 40 the other, a keyboard, and means connected with the first recited means for fore-shortening said keyboard during the downward movement of the frame part.
19. In a compactible typewriting machine, the combination of a frame comprising 45 two parts, one over the other, the upper part carrying printing mechanism including a keyboard movable downward toward the lower frame part, and means for fore-shortening said keyboard during the downward movement of said upper frame part.
20. In a compactible typewriting machine, the combination of a set of type bars, means for operating the same including a 55 set of key levers, and other connections between the key levers and the type bars by which when the key levers are moved rearwardly the type bars are caused to descend.
21. In a compactible typewriting machine, the combination of a series of keys and key levers including telescopic key levers, means extending transversely of the 60 machine for telescoping and extending said telescopic key levers, and a collapsible frame operatively connected with said telescoping and extending means.
22. In a compactible typewriting machine, the combination of a series of keys, means including a space bar for changing the formation of said series of keys to an expanded 70 formation and a contracted formation, and a collapsible frame in which said keys and space bar are mounted and to which said expanding and contracting means is operatively connected.
23. In a compactible typewriting machine, the combination with two relatively collapsible frame-parts, links connecting said frame-parts, type bars mounted in one of said frame-parts, a type rest, and supports 80 46 for said type rest, of means for extending and compacting said type rest with relation to said frame-parts, said means including extensions 48 to certain of said links and horizontal guide links 50 85 pivoted to one of said frame-parts in front of said supports 46.
24. In a compactible typewriting machine, the combination with a compactible keyboard and a frame comprising side bars 90 57 and a transverse bar 54, said side bars being made in telescopic sections, of racks on said sections; pinions, one running between the racks of the two sections of each side bar; and means for further compacting the 95 machine operatively connected with said pinions.
25. In a compactible typewriting machine, the combination of a compactible set of printing keys, a space-frame comprising a 100 space bar and side bars made in telescopic sections, racks on said telescopic sections, pinions one running between the two racks of each side bar, and means for further compacting the machine operatively connected 105 with said pinion.
26. In a compactible typewriting machine, the combination of a compactible set of printing keys, a space-frame comprising a space bar and side bars made in telescopic 110 sections, flanged racks on said telescopic sections, pinions one running between and guided by the two flanged racks of each side bar, and means for further compacting the machine operatively connected with said 115 pinion.
27. In a compactible typewriting machine, the combination of a compactible set of printing keys, a space-frame comprising a space bar and telescopic side bars, racks on 120 said telescopic side bars, pinions one running between the two racks of each side bar, means for further compacting the machine, and connections including links 65 between said pinions and said further compacting 125 means, said links allowing of the operation of the space-bar for spacing purposes without affecting the compacting mechanism.

28. In a compactible typewriting machine, the combination of a set of type bars, a type rest movable to two positions to extend and compact said set of type bars, a set of printing keys, means for compacting said set of printing keys, and connections including bell cranks 67 between said key-compacting means and said type rest.

29. In a compactible typewriting machine, 10 the combination of a set of type bars, a type rest movable to two positions for extending and compacting said set of type bars, means for further compacting the machine, and connections including the 15 geared segments 70 and 71 between said further compacting means and said type rest.

30. In a compactible typewriting machine, the combination of a set of type bars; a 20 type rest movable to two positions to extend and compact said set of type bars; controlling means for said type rest including links 50 and toothed segments 71; a set of

printing keys; means for compacting said set of keys; and connections from the last 25 recited compacting means to said segments 71, said connections including the levers 67 having toothed segments 70 thereon.

31. In a compactible typewriting machine, the combination with telescopic printing key 30 levers, a space-frame including a space bar and telescopic side bars, said space bar serving to telescope said key levers, of a cross bar for extending said telescopic key levers, and links connecting said cross bar 35 with said side bars and adapted to allow of the operation of said space bar for spacing purposes without bodily moving said cross bar.

Signed at Washington, in the District of 40 Columbia, this 28th day of June, A. D. 1918.

JOHN H. BARR.
